ADJUSTABLE WRITING IMPLEMENT

Filed Oct. 22, 1930

UNITED STATES PATENT OFFICE

FRANK FUREDY, OF PENN-WYNNE, PENNSYLVANIA, ASSIGNOR OF ONE-HALF TO
GEORGE M. HESSDOERFER, OF PHILADELPHIA, PENNSYLVANIA

ADJUSTABLE WRITING IMPLEMENT

Application filed October 22, 1930. Serial No. 490,478.

My invention relates to adjustable writing implements in which one or two colored leads may be employed.

A purpose of my invention is to provide a two color writing implement in which standard leads may be employed for immediate selective use, that is, by turning the cap end of the pencil in one direction to feed forwardly one lead, or in the opposite direction to feed forwardly another lead.

A further purpose is to fasten a spring pocket clip to the body of a pencil without the use of rivets or the like.

A further purpose is to feed the different leads by an integrally-threaded sleeve, the upper half of the sleeve being threaded in one direction and the lower half being threaded in an opposite direction.

A further purpose is to provide a double tracked guide within the threaded sleeve member, adapted to guide and laterally support the feed rods of lead holders.

A further purpose is to provide the feed rods with outwardly directed spring-pressed fingers adapted to ride in the groove in the sleeve.

A further purpose is to apply spring pressure to a cap-receiving ferrule to take up wear at the top of the body portion of the pencil.

A further purpose is to place a holder for spare leads near the point of the pencil.

A further purpose is to provide an internally grooved sleeve spun into place in the tip of the pencil.

A further purpose is to provide a two color pencil that is easy of manufacture and simple in construction and which well meets the needs of service.

Further purposes will appear in the specification and in the claims.

I have elected to show one only of the different forms of my invention, selecting however a form that is practical and efficient in operation and which well illustrates the principles involved.

Figure 1 is a side elevation of my improved pencil.

Figure 2 is a sectional elevation taken on the line 2-2 of Figure 1.

Figure 3 is a sectional elevation taken on the line 3-3 of Figure 2.

Figure 4 is a sectional plan view taken on the line 4-4 of Figure 3.

Figure 5 is a sectional plan view taken on the line 5-5 of Figure 3.

Figure 6 is a detached perspective view of my pencil.

Figure 7 is a fragmentary sectional top plan view taken on the line 7-7 of Figure 2.

Like numerals refer to like parts in all figures.

Describing in illustration and not in limitation and referring to the drawing:

My pencil is particularly well adapted for use when two colors are desired but has another advantage in that two leads of the same color may be inserted for use and one lead may be used as an auxiliary lead.

Two leads have been used before in pencils, but to the best of my knowledge I am the first to use a pencil that by turning a portion thereof in either of two directions, different standard leads may be brought into writing position.

My pencil comprises a tubular casing 10 bored at 11 and counterbored at 12. A sleeve 13 is fixed in the bore 11 and a magazine 14 for leads is inserted into the counterbore 12.

A hollow spacer 15 is fixed above and supported on the sleeve 13 and registers flush with the upper end 16 of the tubular casing 10. A hollow operating top 17 is 85 rotatably mounted within the upper end of the spacer 15 with which its downwardly projecting hollow extension 18 engages.

This extension 18 acts as a terminal for and is connected to rotate with the upper end of a continuously grooved sleeve 19. The sleeve may be soldered to it and at its upper end extends at 20 into the hollow of the top 17. The hollowing of the top forms a ferrule 21.

A double-track guide 22 is mounted inside the grooved sleeve 19 and at its bottom 23 registers with the bottom 24 of the lead holder 14. At its top the guide 22 extends somewhat above the sleeve 19 and 100

carries two outwardly extending projections 25 which may be integral with the guide 22 so as to hold a spring abutment (in the form of a washer 26) about the guide 22.

5 Surrounding the guide 22 and between the washer 26 and the bottom 27 of the hollow of the top 17, I place a spiral spring 28, which is centered at its bottom about the projection 20 of the grooved sleeve 19.

10 It will be evident that the ferrule 21 is resiliently pressed by the spring 28 against the inner and end surfaces of the spacer 15. The guiding sleeve 19 is firmly held in the ferrule. In this way the sleeve 28 provides

15 a brake action, tending to maintain the sleeve 19 in any angular position in which it is set, and preventing shifting of the setting of the operative lead holder during use of the pencil. The frictional engagement

20 between the ferrule and the hollow spacer 15 occurs over a relatively wide surface so that the spring 28 need not be of heavy construction.

At its lower end the guide 22 is split to 25 form two outwardly extending projections 29 that fit into vertical slots 30 in the projecting end 31 of the lead magazine 14 to firmly hold the sleeve 19 in place between the upper and lower ends of the pencil.

30 Above the washer 26 in the ferrule 21 I insert an eraser 32 of rubber or the like. This structure above the top of the body 10 is enclosed by a top cap 33 held in place about the ferrule 21. The upper end of 35 the cup is vertically slotted at 17' for the double purpose of allowing frictional engagement with the cap 32 and resiliently holding the rubber.

30 The walls of lead magazine 14 extend 40 downwardly at 34 and are ribbed at 35. In order to permit use of a casing of smaller diameter than could otherwise be used, the thread 36 is interrupted to allow for insertion of spare leads in the spaces 37 in 45 the magazine.

At its upper end the holder terminates in a flange 14' fitting the counterbore 15 and at its top engaging the bottom of the inner sleeve 13. The leads at their inner 50 ends rest against the flange 14' and at their outer ends against the threaded washer 39.

A hollow tapered tip 38 carries a threaded washer 39. The tip is spun into or otherwise locked about the washer as seen at 40 and the tip 41 as a whole is threaded upon 55 the thread 36 of the lead magazine 14.

The washer 39, being securely held in place, acts as a support for the leads in the magazine 14 when the tip 38 is in place 60 on the pencil.

An important feature of my invention is the construction of the lead-feeding mechanism, which comprises the sleeve 19, guide 22 and spring-pressed lead carriers 42 and 43.

The sleeve 19 is provided with relatively reversed internal spiral guiding grooves 44 which may be and, as illustrated, are, continuous, one with the other, and which are most conveniently in the form of grooves. 70

In the best form known to me this spiral track starts at its upper end with a number of turns 45 of slight pitch, it then assumes a much greater pitch at 46 until reaching the center of the sleeve, where at 47 the 75 spiral is reversed in direction for a number of turns at 48 at a slight pitch and then assumes a greater pitch at 49 in the changed direction. The two operating feed grooves 47 and 49 are thus of preferably the same 80 pitch but in the opposite direction. The lower groove extends to the end of the sleeve.

The lead carriers 42 and 43 at their upper 85 ends present spring fingers 50 and 51 which press resiliently against the bottom of the spiral groove, the finger 50 riding in the upper half (groove portions 46 and 47) of the sleeve 19 and the finger 51 riding in the lower half (groove portions 48 and 49) thereof. 90

At the lower ends 52 of the lead carriers I provide sockets 53 in which the leads 54 are securely held by spring action on the socket, the spring action being secured by slitting of the socket at 55. 95

The sockets are free to move vertically with respect to the carriers 51 and 52 because the carriers fit loosely into the sockets. Movement is limited by reason of pins or projections on the carriers fitting into slots 100 57 in the sockets, but the sockets cannot be come detached from the carriers.

Near the top of the pencil I apply a clip 58, bent laterally at 59 with a downward projection 60 and, for economy of space, an 105 inset portion in the form of a notch 61. Whether this be inset or not, the lower end carries a lateral projection 62 fitting into the interior of the body 10 through a slot 63 in the body. 110

The intermediate shank (inset portion) rests in a vertical groove 64 in the side of the spacer 16 and the lateral projection 62 fits into a slot 65, engages the bottom of the inner sleeve to hold the clip in place. It 115 will be obvious that the clip is securely held in place to the pencil without rivets or other fastening means which would tend to break or split the casing or body.

When lead is to be inserted the operator 120 removes the tip thus making the leads within the lead holder accessible so that one of them can be removed. He then screws out the lead carrier bringing the socket within easy reach, pushes the socket back to discharge 125 any stub of used lead which may be in there and subsequently pulls the socket forward and inserts the lead into the socket.

When the leads have been placed in position and the tip has been replaced, the cap 130

32—or if it has been removed to give access to the rubber, the cupped member 14—is turned in one direction to project one of the leads or in the opposite direction to project the other of the leads. In either case the projection of one automatically withdraws the other.

It will be evident that the spring members 50 and 51 not only insure smooth and reliable engagement with the internal grooves to move the lead carriers forward and back but clean the interior of the thread paths of burs or other obstacles or ride over these obstacles when they are not readily removed.

It will be clearly seen that my pencil has an approximately direct line lead feed due to the arrangement of the lead carrier bars in the sleeve.

20 The sockets at the ends of the lead carrier bars, allow for slight resilient movement of the leads which is necessary on account of the slight converging of the leads as they are projected through the tip of the pencil.

25 This angular movement of the lead, being very slight, allows the lead to be presented through the tip of the pencil at an angle that is practically unnoticeable.

It will be evident that my invention provides a strong, simple and compact projecting holder for the pencil and makes possible the use of two leads of different color or of two leads of the same color of which one can be projected when the other has been used to its limit without waiting to refill with lead.

In view of my invention and disclosure variations and modifications to meet individual whim or particular need will doubtless become evident to others skilled in the art, to obtain all or part of the benefits of my invention without copying the structure shown, and I, therefore, claim all such in so far as they fall within the reasonable spirit and scope of my invention.

Having thus described my invention, what I claim as new and desire to secure by Letters Patent is:—

1. In an adjustable pencil, a casing, a feed sleeve considerably smaller in diameter than the casing within the casing and spaced therefrom, having internal spiral grooves upon it, on opposite sides of an intermediate point, one right handed and the other left handed, lead holders engaging respectively with the two grooves, guides for the lead holders within the sleeve pressing them into engagement with the grooves, means for turning the sleeve to cause one lead holder to move in one direction and the other in the opposite direction and a tip directing and supporting one of the leads at a time.

2. In an adjustable pencil, a casing, a feed sleeve considerably smaller in diameter

than the casing within the casing and spaced therefrom, having internal spiral grooves upon it, on opposite sides of an intermediate point, one right handed and the other left handed, the groove at the upper end of each spiral being of slow pitch, spring pressed lead holders engaging respectively with the two grooves, guides for the lead holders within the sleeve pressing them into engagement with the grooves, means for turning the sleeve to cause one lead holder to move in one direction and the other in the opposite direction and a tapered tip directing and supporting one of the leads at a time.

3. In an adjustable pencil, a casing, a feed sleeve considerably smaller in diameter than the casing within the casing and spaced therefrom, having spiral grooves within it on opposite sides of an intermediate point, one right handed and the other left handed, lead holders within the feed sleeve engaging respectively with the two grooves, guides for the lead holders pressing them into engagement with the grooves, means for turning the sleeve to cause one lead holder to move in one direction and the other in the opposite direction and a tapered tip directing and supporting one of the leads at a time.

4. In an adjustable pencil, a casing, a feed sleeve considerably smaller in diameter than the casing within the casing and spaced therefrom, having spiral grooves within it on opposite sides of an intermediate point, one right handed and the other left handed spring pressed, lead holders within the sleeve engaging respectively with the grooves in the sleeve, guides for the lead holders pressing them into engagement with the grooves, means for turning the sleeve to cause one lead holder to move in one direction and the other in the opposite direction and a tapered tip directing and supporting one of the leads at a time.

5. In an adjustable pencil, a casing, a feed sleeve considerably smaller in diameter than the casing within the casing and spaced therefrom, having concaved spiral grooves within the sleeve on opposite sides of an intermediate point, one right handed and the other left handed, lead holders lying within the sleeve and engaging respectively within the concavities of two grooves, guides for the lead holders pressing them into engagement with the grooves, means for turning the sleeve to cause one lead holder to move in one direction and the other in the opposite direction and a tapered tip directing and supporting one of the leads at a time.

6. In an adjustable pencil, a casing, a feed sleeve considerably smaller in diameter than the casing within the casing and spaced therefrom, having spiral grooves upon it on

- opposite sides of an intermediate point, one right handed and the other left handed, lead holders engaging respectively with the two grooves, a rod within the sleeve having guides on its opposite sides for guiding the lead holders and pressing them into engagement with the grooves, means for turning the sleeve to cause one lead holder to move in one direction and the other in the opposite direction and a tapered tip directing and supporting one of the leads at a time. 5
7. In an adjustable pencil, a casing, a feed sleeve considerably smaller in diameter than the casing within the casing and spaced therefrom, having spiral grooves upon it on opposite sides of an intermediate point, one right handed and the other left handed, lead holders having reversely turned spring contact fingers engaging with the grooves, 10
- 15 20 from inside the sleeve, guides for the lead holders pressing them into engagement with the grooves, means for turning the sleeve to cause one lead holder to move in one direction and the other in the opposite direction and a tapered tip directing and supporting one of the leads at a time. 25
8. A feed sleeve of thin wall tubing for an adjustable pencil having a single internal thread at each end oppositely spiralling on opposite sides of an intermediate point, a 30 guide bar within the sleeve having guides on opposite sides of the bar and two lead holders, one fed within each guide and engaging with the grooves within the sleeve. 35
9. A feed sleeve, a guide bar within the sleeve having guides on its opposite sides and the bar split at its ends to form lateral extensions, a terminal washer on the guide bar, held thereon by the lateral extensions. 40
10. A feed sleeve for an adjustable pencil, a ferrule within which the sleeve projects, a guide bar rotatably secured to the

sleeve at its lower end and extending beyond the sleeve at its upper end, a disc secured to the guide bar extension, and a spring mounted between the disc and the bottom of the ferrule. 70

11. A feed sleeve for an adjustable pencil, a casing about the sleeve, a ferrule within the casing secured to the feed sleeve, a guide within the sleeve projecting beyond the sleeve into the ferrule, an abutment upon the guide and a spring about the sleeve engaging the abutment at one end and the ferrule at the other to take up wear on the top of the casing. 75

12. A feed sleeve, a guide bar within the sleeve having guides on its opposite sides, a terminal washer fastened at one end of the guide bar and a lead magazine at the other end of the guide bar, the ends of the bar being split and turned at right angles 80 to secure the terminal washer at one end and the lead magazine at the other end to the guide bar. 85

13. In an adjustable pencil, a casing, a feed sleeve within the casing considerably 90 smaller in diameter than the casing, having a spiral groove upon the inside of the sleeve near each end of the sleeve, one right handed and the other left handed, lead holders within the sleeve, movable longitudinally of the 95 sleeve and gripping leads and means following the groove for moving the lead holders longitudinally. 100

14. In a pencil, a casing, a sleeve within the casing in spaced relation to the casing, 100 a magazine between the sleeve and the casing, an abutment engaging one end of the magazine and means extending longitudinally through the sleeve for positioning the other end of the magazine, said means 105 being spread outwardly. 110
